TELEPHONE CALL TIMER

George Nagrodsky, 85 Shields Ave.,
Williston Park, N.Y. 11596

Filed Dec. 18, 1967, Ser. No. 9,834

Term of patent 14 years

U.S. Cl. D26—14

Int. Cl. D10—03; D14—03

FIG. 1 is a perspective view of a telephone call timer embodying my new design and showing its relation to a telephone handset which is shown in phantom, and

FIG. 2 is a rear elevation view thereof, taken at reduced scale.

The broken lines are shown for illustrative purposes only.

I claim:

The ornamental design for a telephone call timer, as shown and described.
